DESIGN FOR A LADDER BOOT

Walter P. Regan, Lowell, Mass.

Application April 10, 1947, Serial No. 138,286

Term of patent 7 years

(Cl. D15—8)

To all whom it may concern:

Be it known that I, Walter P. Regan, a citizen of the United States, residing at Lowell, in the county of Middlesex and Commonwealth of Massachusetts, have invented a new, original, and ornamental Design for Ladder Boot, of which the following is a specification, reference being had to the accompanying drawing, forming part thereof.

Fig. 1 is a side elevation of a ladder boot, showing my new design.

Fig. 2 is an end elevational view thereof as from the right of Fig. 1 and

Fig. 3 is a plan view.

I claim:

The ornamental design for a ladder boot, as shown.

WALTER P. REGAN.
